UNITED STATES PATENT OFFICE.

SILVIUS J. PIANTONI, OF NEW YORK, N. Y.

DESIGN FOR A TELEPHONE-BONNET.

49,100.

Specification for Design.

Patented May 23, 1916.

Application filed March 29, 1916. Serial No. 87,630. Term of patent 3½ years.

To all whom it may concern:

Be it known that I, SILVIUS J. PIANTONI, a subject of the Emperor of Austria-Hungary, residing at New York, in the county of New York and State of New York, have invented a new, original, and ornamental Design for a Telephone-Bonnet, of which the following is a specification, reference being had to the accompanying drawing, forming part thereof.

Figure 1 is a front view of the bonnet, showing my new design, and Fig. 2 is a side view of the telephone bonnet.

I claim:—

The ornamental design for a telephone bonnet as shown.

SILVIUS J. PIANTONI.
